CLAIM

The ornamental design for a bulbocavernosus muscle trainer for strengthening and toning the vaginal-sphincter muscle, as shown and described.

DESCRIPTION

FIG. 1 is a front elevational view of a bulbocavernosus muscle trainer for strengthening and toning the vaginal-sphincter muscle showing my new design;

FIG. 2 is a right-side elevational view, the opposite side being a mirror image; and,

FIG. 3 is a rear elevational view thereof.
